Primary Examiner — Prabhakar Deshmukh(74) *Attorney, Agent, or Firm* — Cooley LLP(57) **CLAIM**

The ornamental design for a sling latch, as shown and described.

DESCRIPTION

FIG. 1 is a perspective view of an embodiment of the sling latch;

FIG. 2 is a top view thereof;

FIG. 3 is a bottom view thereof;

FIG. 4 is a front view thereof;

FIG. 5 is a back view thereof;

FIG. 6 is a left side view thereof; and,

FIG. 7 is a right side view thereof.

The broken lines immediately adjacent the shaded areas represent the bounds of the claimed design while all other broken lines are directed to environment and are for illustrative purposes only; the broken lines form no part of the claimed design.
